Filed May 28, 1964, Ser. No. 371,023
13 Claims. (Cl. 12—145)

This invention comprises a novel method of controlling the height and alignment of the back portion of a shoe upper during the operations of assembling it on a last, preparatory to lasting it to the insole of a shoe. The method is applicable to boots or shoes of any type or height, provided they contain an insole. It may be designated as "Precision Tab Assembly."

The present practice of most shoe factories makes the first shoemaking operation that of assembling a stitched upper and a counter on a last to the bottom of which a fitted insole has already been attached. In most cases the assembling operator must insert a freshly cemented counter into the counter pocket between the counter lining and the back of the upper. He then inserts the last within the stitched upper and completes his assembly by a nailing or tacking operation. In hand-assembling the assembler drives by hand two tacks through the back of the lasting margin of the upper and the back end of the insole, which tacks are clinched over by the metal heel plate on the last bottom. In machine assembly the machine drives these same two tacks, and commonly also drives a nail through the back of the upper and into the last near the top of the back seam.

These tacking operations perform the following functions:

- (1) Temporary attachment of the upper to the last.
- (2) Establishment of the back height of the lasted shoe.
- (3) Alignment of the back seam of the upper on the last. The tacking incorporates permanently into the shoe the results of the operator's judgment and skill in assembling the back of the upper to the desired height and alignment. Let us examine the problems which face him in present practice.

First, the depth to which the assembler inserts the counter depends on his judgment and experience, as he has no match-marks to guide him. Second, he must gauge the height of the upper on the last by a mark on the spine of the last, or by the amount of the lasting margin of lining, counter and upper which he folds down over the back end of the insole. Third, he must gauge the alignment of the back seam while the upper is held in loose contact with the last. He then must place the last, held upside down with the upper loosely draped thereto, on a spindle either of a lasting machine or on his bench. The tacking is then done, by machine or by hand, while the shoe is so positioned that the operator cannot see the top of the upper or the top of its back seam.

The assembling machines now commonly used in shoe factories are little more than mechanical nail drivers. Their design forces the operator to finalize his work by a nailing operation while he cannot see the only guide mark he has. The hand assemblers are in nearly as bad a fix. The natural result is that many shoes go through the factories with pairs of unequal back heights, and often with the back seams out of proper alignment. These faults, incorporated in the shoes at the first operation in the lasting room, make some of the subsequent operations difficult, and add to the cost of the shoes.

Many attempts have been made in the past to provide on a shoe last a mechanical means of controlling the back height and the alignment of a shoe upper. These

2

past efforts at control have won only limited acceptance by shoe manufacturers, primarily for two reasons:

- (1) The use of some of these height controlling means introduces an added labor operation, and
- (2) The controlling means must be removed from the last when the manufacturer wants to use this same last for a boot with a higher back.

Our present invention requires no modification of the lasts on which the shoes are made. Its novel features are limited to the ways in which certain components of the shoes are prepared and assembled into the finished product.

The pattern makers who lay out the components of shoe uppers take care to provide match-marks on each of these parts so that they may be assembled and stitched together accurately. But in their design of those edges which are to be pulled over a last and lasted to an insole the pattern makers have never provided anything more than a generous lasting allowance to compensate for the variations caused by the lack of uniformity inherent in the present assembling procedures. These procedures have been used for many years, without any improvement.

The primary purpose of our present invention is to provide the shoemaker with a means of assembling on the last with uniform accuracy a stitched or closed upper and an insole. We have discovered a shoemaking method by which this result may be achieved, a method which controls both the height and the lateral alignment of the back seam of the upper in a single operation. The accuracy of our method is equivalent to that with which the various parts of the upper are assembled and stitched together. The essential feature of our invention is the use of one of the component parts of the upper, preferably the one that is in contact with the back spine of the last when on the last, as a measuring means to measure down along the back of the last spine and past the back end of the insole, and thence forward to a predetermined point on the under side of the insole.

In the design of any shoe the desired height of the back and the thicknesses of the specified components are all predetermined. Therefore the distance comprising the sum of the back height measured peripherally on the curve of the spine of the last, the thickness of the insole and any other between-substance, and a specified measurement forward from the back end of the insole can also be predetermined. With this total distance being determined for any given shoe, it can be reproduced in the component of the upper, or a combination of such components.

The practice of this invention may vary slightly, depending on which component is used as the measuring means. Either the counter lining or the outer integument of the upper itself may serve this purpose. Similarly, if, prior to the assembling of the upper on the last, the counter is cemented or otherwise attached to the upper at a pre-marked height and center line, the counter could be a part of the measured distance. The practice, but not the principle, for shoes with flat-lasted heel seats will be different from that used in shoes welted around the heel seat. The procedures and variations will be readily apparent to one skilled in the art from the following description of a preferred example.

We prefer to use the counter lining for the measuring means. The lining is the innermost component of the upper contact with the back of the last, and one which often causes wrinkles in the finished shoe if not drawn tight to the last, a drawback which is practically eliminated by our new assembling procedure. The counter linings are commonly stitched to the back parts of the uppers along the top seam. As it is very difficult to match the top edge of the pre-cut lining exactly to the

varying curve of the top of the upper, it is common practice to let this stitching follow somewhat below the upper edge of the lining, and to trim off a marginal top strip of the lining of varying width either by undertrimming done simultaneously with this stitching, or subsequently as a separate operation. Therefore, if the counter lining is to be used as the means of measuring the back height of an upper, the measurement must be established and marked on the lining after it has been stitched to the upper. Another consideration in this connection is that for many or most shoes the counter lining is prepared to fit the domed shape of the back end of the last by removing a vertical gore of material from the center of the lower half of the lining and then closing that gore by stitching its edges together.

Two alternate methods are available for fitting a counter lining to serve also as the means of controlling the back height of an upper and the vertical alignment of its back seam. First, a tab of any suitable material may be stitched or otherwise attached to the lower axially central portion of the lasting margin of the lining. This tab should extend downwardly, and hence forwardly after it is lasted under the insole, about one inch beyond the normal lower edge of the lining. This tab should preferably be attached to the lining before the latter is stitched to the upper. The end of the tab should carry a match mark or index mark such as V-notch, located on the center line of the lining at a predetermined distance from the central point of the top edge of the upper. Alternatively a match mark may be cut into the lasting margin of the lining without the added tab. This alternate step saves the cost of attaching a tab, but makes the practice of our process, as described below, a little more exacting.

The underside of the insole which is exposed on the last bottom should be marked with a transverse score line at a predetermined distance, preferably an inch and one-eighth forward from its back end, and a center line. In assembling the upper on the last line the index mark on the lining is drawn forward to the registration or intersection of the gauge mark on the insole bottom, and the lower margin of the lining is then fastened to the insole, by tacking, stapling or other means.

The correct height and alignment of the back of the shoe is established by the following:

(1) Correct measurement from the top of the upper to the index mark on the bottom of the lining.

(2) Correct positioning of this index mark to the gauge mark on the insole, both longitudinally and laterally.

The stapling of the counter liner to the bottom of the insole is nothing more than what is now done with the bottom tacks used in the present assembling procedures. But it should be noted that by our method this attaching is done only after the operator has brought the back of the upper into its designed relationship with the insole, both longitudinally and laterally, with predetermined measurements and match marks. As done heretofore the operator has no visible guide marks and a minimum of control of the upper at the time of nailing.

The procedure for measuring the predetermined distance on the counter lining and the formation of the index mark is of secondary importance. The two operations can be performed simultaneously, together with accurate control of the centering of the match mark, by a relatively simple mechanism herein shown. The marking of a score line and center line on an insole is a simple matter. For shoes to be welted around the heel seat this score line could be located on the feather at the back end of the insole, using the alternate method of matching-marking the lining in its lasting margin without the added tab.

We prefer to make the tab about one and three-eighths inches long and about three-quarters of an inch wide, and to stitch one end of the tab to the lasting margin of the counter lining after the lining has been gored and the

gore closed by stitching. If the lining is not to be gored, the tab may be an integral extension of the lining. A tab of this size is long enough to be drawn over a sewing rib on the back end of an insole in a shoe which is to be welted around the heel seat, and then brought down to a gauge mark in the insole inside the rib. For shoes with welted heel seats the tabs may be cut away inside the sewing rib after heel lasting operation so the channel guide of the welting machine will have a free passage around the heel seat. A tab of the size specified above provides ample material to allow for normal variations in stitching it to the lining, and it also gives the assembler a good means of drawing the lining smoothly over the end of the insole.

Our new method as described above is readily adapted to the use of either flat or pre-molded counters, which latter have specific advantages for use with welted heel seats.

Better lasting of counters can be readily achieved with our new method of assembly which establishes a center line visible on the underside of the back end of each insole. If each counter is likewise marked with an index mark in the center of its lower edge the assembler has a positive guide to the correct lateral positioning of the counter. As stated above, it is possible to use the counter as a part of the measuring means. To do so it is convenient to measure and mark the counter lining, or the upper, for the correct positioning of the center point of the top edge of the counter, and to cement the counter thereto before assembling the upper on the last.

It will also be noted that our new method is applicable to shoes or boots of any height, regardless of the height of the lasts on which they are lasted, and that no mark or score line is needed on the spines of the lasts.

We have devised a simple mechanical means of accomplishing in one operation the measuring of the back height of an upper and of establishing on the tab attached thereto the desired index mark, with assurance that this mark will represent correctly the height and center alignment of the back seam of the closed upper. The basic elements of this measuring and marking mechanism are, in combination, a marking means and a specially designed horn which supports the upper and which provides the measuring and aligning means. We prefer to have the marking means arranged to act downwardly on the tab, with the horn extending forwardly and substantially horizontally therefrom towards the operator.

The marking means may be either a simple stamp which simultaneously marks on the tab a transverse score line and a longitudinal center line, or a pinking knife which cuts a V-notch in the end of the tab. If the tab is marked with the combined score line and center line, each line should extend to the edge of the tab so that the lines can be matched to similar lines of a gauge mark on the bottom of the insole. We prefer to mark the tab with a pinked notch having a rounded point which can be centered over the intersection of the score line and center line on the insole.

The measurement accomplished by this mechanism is a distance measured on the inside of a curving line defined by the intersection of a theoretical plane on the centerline of the shoe passed vertically through the irregularly domed back of the upper, plus a distance which can be measured flat on the tab. This back curve of the upper is obvious on a finished shoe, but is most indefinite in a closed upper before it is lasted. The curvature changes as the sides of the back of the unlasted upper are drawn towards each other. The interior vertical curvature of the back of the upper is further complicated by the stitched backseam which closes the backs of most uppers, and often also by a second backseam closing a gore cut in the lower half of many counter linings.

The horn is a key element which makes possible the simultaneous measurement, aligning and marking of the

back of a closed shoe upper. In our mechanism the back of the upper is draped over the horn, with the tab back under the marking device, and the top edge of the upper forward towards the operator. If the horn is made with parallel sides and with its top edge made with a horizontal back end which merges into the anvil under the pinking blade or stamp which marks the tab, an upwardly curved portion in the area which supports the interior of the upper, and a forepart which slopes downwardly, we have found that a horn so constructed will conform to the interior back curve of a shoe upper that is drawn over it. It is obvious that the irregular top contour of the horn as above described reproduces the interior contour of the back of the shoe and the tab attached thereto, and therefore the desired measurement can be established on the top surface of the horn. We provide on the top of the horn a measuring scale, positioned so that its zero point is the location of the gauge mark to be printed on or pinked in the tab. The control measurement is readily obtained by sliding the upper along the horn until the top edge of the upper overlies the desired measurement as shown on the scale. With the upper in that position, the designed measurement is established in the tab by pinking or printing. As an added help we have also provided a movable indicator so that each shoe of a pair, or several pairs calling for the same height, can be more easily match-marked uniformly.

The horn is also the key to the correct alignment of the index mark in the tab, and therefore also the correct vertical alignment of the backseam of the upper in the completed shoe. When the upper is drawn down over the horn the alignment of the backseam, and therefore also the mark to be made in the tab, will be most obvious to and controllable by the operator. With this procedure, any inaccuracy in the attaching of the tab to the lasting margin of the lining or other component is of no consequence, as the index mark will be automatically centered.

The establishment of the gauge mark on the bottom of the insole is simple. We prefer to make this mark with a transverse score line long enough to extend to each side beyond the sides of the tab which will overlie this mark, and a centerline long enough to extend forwardly beyond the end of the tab. For shoes to be welted around the heel the score line could be located on the feather at the back end of the insole, using the alternate method of match-marking the lining in its lasting margin without the added tab. We do not prefer to do so. We prefer to locate the transverse score line one and one-eighth inch forward of the back end of the insole.

Our process of precision tab assembly will be most advantageous and economical to shoemakers making shoes incorporating the skeletal rand insoles described in our co-pending applications Ser. Nos. 278,568 and 310,029. In the earlier of those constructions the core portion of the insole is, and in the latter at least the heel portion of the core, may be removed prior to assembly, thereby leaving the center of the heel seat area of the last bottom exposed through the window thus provided in the insole. For shoes so made no gauge mark need be marked on the bottom of each insole, as a permanent gauge mark may be incorporated on the heel seat area of each last in a location where the gauge mark will be visible through the window. This variation in the practice of our present invention thereby saves the cost of marking each insole.

From the above outline of our novel method it will be obvious that each size of shoes will call for a different measurement which will also be varied by any difference in thickness of insoles. As a practical procedure it is not difficult to specify the correct measurement for each size and style. Sometimes insoles are somewhat longer or shorter than the bottoms of the lasts to which they are to be tacked. Insole tackers commonly match the in-

sole to the toe of the last and to let the heel end fall where it may. In our method such inaccuracies may be easily compensated for by the assembler who folds the bottom of the lining and its tab over the back of the insole.

5 The features and advantages of our invention will be best understood and appreciated from the following description of several examples selected for purposes of illustration and shown in the accompanying drawings, in which

10 FIG. 1 is a view in perspective of the rear end of an upper assembled upon a last in accordance with our improved method,

15 FIG. 2 is a corresponding view in longitudinal section,

FIGS. 3 and 4 are views corresponding to FIG. 1 and showing the index tab attached to the counter rather than the lining,

20 FIG. 5 is a fragmentary view of an upper with the index tab attached to the outer integument thereof,

FIG. 6 is a fragmentary sectional view showing the upper of FIG. 5 on a last, and

25 FIGS. 7, 8 and 9 are views respectively in plan, cross section and longitudinal section showing the mechanism for measuring the upper and marking its tab.

30 In FIGS. 1 and 2 we have indicated how our improved assembling method may be carried out when the index tab is attached to the lining ply of the upper. In these figures is shown the rear end of a last 10 having the usual metallic heel plate 11 and carrying an insole 12 which has been accurately located on the last bottom and secured by insole tacks 13 of which one only is shown.

35 The last 10 is first placed within the upper which as herein shown comprises an outer integument 14 having a back seam 15, a fitted lining ply 16 and a molded counter 17. These parts are united by the usual top seam.

40 The insole 12 is provided with a gauge mark in the shape of a cross 12' of which the longitudinal line indicates transversely the exact center of the insole. The transverse line of the cross is located at a predetermined distance from the desired location of the top of the upper upon the back of the last measured as above explained.

45 The tab 18 is shown as stitched to the lining ply 16 at the center of its concave edges and as carrying an index mark in the form of a V-notch 19 of which the apex is located a measured distance from the top edge of the upper equal to the distance indicated by the gauge mark 12' of the insole.

50 The assembling operation is now carried out by drawing lining 16 with the tab 18 forwardly upon the last until the index mark 19 of the tab registers with the gauge mark 12' of the insole and then attaching the tab to the insole 12 by a staple 20. The tab 18 thus becomes a linking means between the upper and the insole. In this manner the top line of the upper is positively and accurately located at exactly the desired height on the back of the last and the back seam 15 coincides accurately with the centerline of the heel end of the last. The upper is therefore perfectly assembled for pulling-over and other conventional shoemaking operations.

55 60 In FIGS. 3 and 4 we have indicated how our improved assembly method may be carried out when the index or linking tab is attached to a molded counter in the upper.

65 The insole 12, as before, is provided with the gauge mark 12' in the form of a cross. The tab 21 is provided with the V-shaped index mark 22 and attached to the counter 17 at the center of its inturned flange. The counter itself is adhesively secured in the upper between the outer integument 14 and the lining ply. The index mark 22 of the tab is now brought into registration with the gauge mark 12' of the insole and the tab secured by a staple 23 to the insole.

70 75 In FIG. 5 our method is shown as modified by the employment of an insole 28 having a window 29 formed in its heel seat which gives a rand-like aspect to the

insole. A portion of the last bottom is thus exposed to view and on this is placed in measured location a gauge mark 28' in the form of a cross.

The tab 26 carrying the V-shaped index mark 27 is attached to the outer integument 14 of the upper. The tab 26 is drawn forwardly to register the index mark 27 with the gauge mark 28' on the insole and then the tab may be stapled to that portion of the recessed insole at the rear of the window 29.

In FIG. 6 the index tab or link 24 is shown as stitched to the outer integument 14 of the upper. It is assumed to have been drawn forwardly to register its index mark with a gauge mark on the insole 12 and to have been attached to the insole in that section by a staple 25.

In FIGS. 7-9 are shown the operative elements of a machine useful for accurately measuring the upper with its attached tab and for marking or stamping the tab to indicate the desired critical distance from the top line.

The machine has a stationary bed 31 to which is attached a bed plate 32 formed as a part of a forwardly projecting horn 30. The horn has parallel side walls as indicated in FIG. 9 and a transversely curved top wall over which the upper 14, 16 may be draped. The top surface of the horn 30 is also curved longitudinally to approximately the curvature of the inside of the closed upper at its back seam.

An anvil or platen 33 is fastened to the bed plate 32 in line with a reciprocating head herein shown as carrying a V-shaped pinking knife 34 adapted to cut in a tab a V-shaped notch, such as the notch 19 shown in FIG. 1.

Upon the top surface of the horn 30 is placed a scale 35 reading outwardly from a zero point that corresponds to the exact center of the index mark to be formed in or upon the tab. The horn is also grooved for the reception of a sliding gauge 36 which may be set in cooperation with the scale 35 at the desired position in the horn.

As shown in FIG. 8 the closed upper 14 is placed on the horn 30 with its top edge against the gauge 36 and its tab 17 in position upon the anvil 33 where the knife has been operated to form the V-shaped index mark.

Having thus disclosed our invention and described in detail illustrative examples of putting it into effect, we claim as new and desire to secure by Letters Patent:

1. The method of assembling on a last and insole a shoe upper comprising an outer ply and a lining ply having a centrally disposed tab with an index mark therein at a fixed peripheral distance from the top seam of the upper; the method comprising the steps of forming a heel-seat gauge mark at the same peripheral distance from the desired location of the top seam on the back of the last, as the distance indicated by the index mark on the tab, bringing the index mark of the tab into fixed relation to the heel-seat gauge mark, and attaching the tab as thus located to the insole.

2. The method of assembling on a last with an attached insole a shoe upper comprising an outer ply and a lining ply secured together by a line of top stitching and a centrally disposed tab on one of said plies having an index mark at a fixed peripheral distance from the top seam; the method comprising the steps of forming on the insole a gauge mark at the same peripheral distance from the desired location of the top seam with respect to the top of the last, registering the index mark of the tab with the gauge mark of the insole, and attaching the tab to the insole.

3. The method described in claim 2, further characterized by the steps of forming the insole gauge mark so as to indicate the transverse center of the insole and fastening the tab with its index mark in registration therewith.

4. The method described in claim 2, further characterized by the step of forming the insole gauge mark so as to indicate both the transverse center of the insole and a predetermined longitudinal length of the upper from

the top seam to and including the tab, and then fastening the tab with its index mark in registration both transversely and longitudinally with said gauge mark.

5. The method of assembling on a last with an attached insole a closed shoe upper having a centrally disposed tab projecting from its lower edge and carrying an index mark at a predetermined peripheral distance from the top of the upper; the method comprising the steps of forming on the heel seat of the insole a gauge mark at a predetermined peripheral distance from the desired location of the top seam of the upper on the last, drawing the tab over the insole and thereby registering the two marks and then fastening the tab to the insole preparatory to lasting the upper.

10 6. The method of claim 5 further characterized by having the said predetermined distance equal to the sum of (1) the designated height of the top of the upper as measured on its interior vertical curve; (2) the thickness of the insole and heel pad to be placed in the upper; and (3) the distance from the back end of the insole to the gauge mark marked on its bottom.

20 7. The shoemaking method as described in claim 5 in which the first step is the attachment of the upper to the insole by a linking means formed as an extension of the central lower portion of a component part of the back end of the upper.

25 8. The method of claim 7 further characterized by having a gauge mark marked on the exposed side of the insole at a predetermined distance from its back end.

9. The method of claim 8 further characterized by having the said gauge mark incorporate both a transverse score line and a longitudinal center line.

10 10. The method of controlling the back height of the heel portion of a shoe upper during its assembly to an insole which comprises: providing on a component part of the back of the upper a linking means having an index mark near its outer end at a predetermined distance below the top edge of the back of the upper; drawing the said linking means over the back end of an insole having on its under side a gauge mark located at a predetermined distance forward from the back end of said insole until the index mark on the linking means is in overlying registration with the gauge mark on the insole; and thereupon fastening the upper to the insole.

11 11. The method of controlling both the back height and the lateral alignment of the heel portion of a shoe upper during its assembly to an insole which comprises: providing on a component part of the back of the upper a linking means having near its outer end a gauge mark located both a predetermined distance below the top edge of the upper and coincident with the center line of the back of the upper; drawing the said linking means over the back end of an insole having a gauge mark located both a predetermined distance forward from the back end of the said insole and coincident with the center line thereof until the index mark on the linking means is in overlying registration with the gauge mark on the insole; and thereupon fastening the upper to the insole.

12 12. The method of controlling the back height of the heel portion of a shoe upper during its assembly upon an insole having an opening through a portion of its heel seat area, which comprises: marking on the bottom of a last the gauge mark; temporarily attaching the above-described insole to the bottom of the said last; providing on a component part of the back of the upper a linking means having an index mark near its outer end at a predetermined distance below the top edge of the upper; drawing the said linking means over the back of the above-said insole and last until the index mark on the linking means is in overlying registration with the gauge mark on the said last; and thereupon fastening the upper to the insole.

13. The method of controlling both the back height and the lateral alignment of the heel portion of a shoe upper

during its assembly to an insole having an opening through a portion of its heel seat area, which comprises: marking on the bottom of a last a gauge mark; temporarily attaching an insole to the bottom of said last; providing on a component of the upper with a linking means having near its outer end an index mark indicating both a predetermined distance from the top edge of the upper and the center line of the back of the upper; drawing the linking means over the back end of the above said insole and last until the index mark on the linking means is in overlying registration with the gauge mark on the said last; and thereupon fastening the upper to the insole.
